DESIGN FOR A TEXTILE FABRIC

Robert P. Baggaley, Paterson, N. J.

Application May 28, 1941, Serial No. 101,201

Term of patent 3½ years

To all whom it may concern:

Be it known that Robert P. Baggaley, a citizen of the United States and resident of Paterson, in the county of Passaic, State of New Jersey, has invented a new, original, and ornamental Design for a Textile Fabric, of which the following is a specification, reference being had to the accompanying drawing, forming part thereof, and in which, the single figure of the drawing illustrates a textile fabric, embodying my new design.

I claim:

The ornamental design for a textile fabric, substantially as shown.

ROBERT P. BAGGALEY.
